UNITED STATES PATENT OFFICE

ELMER E. HICKEN, OF COLLINGSWOOD, NEW JERSEY

TENDER TANK

Application filed April 7, 1931. Serial No. 528,390.

My invention relates to certain improvements in tender tanks for locomotives.

One object of my invention is to so design the tank that the capacity of the tank is increased without increasing the overall dimension.

A further object of the invention is to facilitate the manufacture of the tender and to reduce the number of rivets in the water portion of the tender.

A still further object of the invention is to decrease the height of the cylindrical type tank and provide a running board at each side of the raised portion of the tank, thus lowering the centre of gravity somewhat.

A further object of the invention is to so design the top dash plates that they will reinforce the upper portion of the tender tank.

A still further object of the invention is to make the tank semi-cylindrical in form with a horizontal top, the top being less in width than the overall width of the tank.

In the accompanying drawings:

Fig. 1 is a side view of my improved tender tank illustrating my invention;

Fig. 2 is an end view of the forward end of the tank;

Fig. 3 is a sectional view on the line 3-3, Fig. 1;

Fig. 4 is a sectional view on the line 4-4, Fig. 3;

Fig. 5 is an enlarged side view of the rear end of the tank, showing the method of forming the rear dished head;

Fig. 6 is a diagrammatic sectional view showing one-half of the tank and illustrating the method of forming the dished head, so as to continue the running board to the end of the tank; and

Figs. 7, 8 and 9 are sectional views illustrating modifications of the running board section of the tank, showing the different forms of flanges.

1 is the base frame of the tender, which extends the full length thereof and in the present instance is made hollow to provide additional water space for the tender tank. The width of this base frame is less in width than the body of the tank, as clearly shown in Fig. 3. 2 is the water section of the tank

and 3 is the fuel section. Dividing the water section from the fuel section are vertical walls 4 having inclined extensions 5 which are secured at their upper ends to the outer walls 6 of the tender tank. At the rear of the fuel section is a vertical division wall 7 having an inclined extension 8 of the usual type. The fuel section of the tank can be made as shown in the drawings, or may be designed so as to receive an automatic stoker without departing from the essential features of the invention.

At the forward end of the tank in the present instance, are rectangular boxes 9. The water section of the tank is extended on each side of the fuel section, as shown at 2a and under the fuel section as shown at 2b. The lower portion of the tender tank is semi-cylindrical in cross section. Each side plate 6 is curved at its lower end and is flanged at 10, the flanges being secured to the base frame 1 by welding or other suitable means. The upper portions 11 of the plates 6 are vertical, the plates extending the full height opposite the fuel section but terminating short thereof at the main water section, as clearly shown in Fig. 3.

12 is the top of the water section of the tank. The main portion of this top is less in width than the body of the tank but higher than the side walls, as shown in Fig. 3. This top is preferably made of a single plate bent to form a flat central top section 13, vertical sides 14 and horizontal portions 15, which form a running board at each side of the central portion.

The side plates 6 extend above the running board sections 15 of the top plate, so as to form flanges 16, as clearly shown in Fig. 3. This construction dispenses with the usual T-iron extension, which is used as a flange in the ordinary type of tender tank.

A rear dished head 17 in the present instance is shaped and welded to the horizontal top plate 12 and the base frame 1. The tread plates at each side of the tender extend to the rear of the tank, the rear dished head 17 being cut out to receive the tread plates, and the head is welded to the tread plate, as shown in Fig. 1.

In making the dished rear head 17, the head before being shaped is of greater diameter than the body of the tank, as shown by dotted lines in Fig. 6. Then the top is cut off on the line "a", so as to be level with the top section 13 of the tank and the bottom is cut off on the line "b" and welded to the projecting rear portion of the base frame 1. The dished head is cut at the sides to conform to the shape of the side walls 6 of the tender and is cut away at "c" for the extension 30 of the vertical side plates 14 and for the running board 15 and the dished head is welded on the line "c" and welded to the extension 30 of the vertical side plate 14, and the extension of the running board 15. The head is welded to the side plates 6 on the line "d", making the rear end of the tender tank very substantial.

18 are a series of transverse dash plates secured to the side plates 6 by T irons 19. These T irons extend to the underside of each running board section of the top plate. 20 are the upper transverse dash plates, which are connected to the side plates by angle irons 21 and to the running board section 15 by angle irons 22, which are bent to allow for the angle irons 23 which reinforce the joint between the edges of the running board plate 15 and the vertical side plates 6. The dash plates 20 extend into the raised central portion of the top plate 12 and are secured thereto by T-irons 24. The dash plates 20 are preferably flanged at 20a to provide additional stiffness. The portion of the tank directly under the fuel section is reinforced by frames 25 or angle irons which have horizontal portions 26 secured to the base frame 1, and horizontal portions 27 which extend under the fuel section and the side water sections 2a.

Figs. 7, 8 and 9 illustrate modifications of the joints between the side plates and the running board sections of the top plate. In Fig. 7 the side plate 6a has an inturned flange 28, and the section 15a of the top plate extends over this flange and is turned up to form a flange 16a, the two plates being welded or riveted together.

In Fig. 8 the side plates 6b extend above the joint section 15b of the top plate, this section 15b being turned down to form a flange 29.

In Fig. 9 the side plate 6c is extended above the running board section 15c of the top plate, and this section is turned up at 16c to form a flange, which is welded or riveted to the extension of the top plate 6c.

The tender tank can be designed to receive stoker mechanism if desired without departing from the essential features of the invention.

By the above construction, in order to decrease the height of the cylindrical type of tender tank as shown by dotted line *a*, Fig. 6,

the upper portion A of a cylindrical tank is removed, and the loss of capacity is made up by the sections B and C, thus lowering the centre of gravity somewhat.

I claim:

1. The combination in a tender tank, of side plates; a top plate greater in height than the side plates and less in width than the tender, and having a depressed portion at each side secured to the side plates; and flanges formed at the junction of the top plate and side plates, the depressed portions of the top plate forming the running board of the tender.

2. The combination in a tender tank having side walls, of a top plate, the side walls being curved at their lower ends and having vertical portions at their upper ends secured to the top plate, the top plate being less in width than the tank and having depressed portions at each side secured to the side walls of the tank and forming the running boards of the tender; a dished rear head welded to the top plate and to the base frame, the dished head being cut out and the vertical portions and the portions forming the running boards being extended beyond the side plates and welded to the cut out portions of the rear dished head.

3. The combination in a tender tank having a water section, of side plates forming the side walls of the water section; a top portion greater in height than the side portions and of less width than the body of the tank; running boards at each side of the tank extending from the top portion to the side walls of the tank; upper dash plates extending from one side of the tank to the other and extending into the space formed by the top portion of the tank; and angle members securing said dash plates to the sides of the tank and to the top portion and acting to reinforce said top portion.

4. The combination in a tender tank having a water section, of side plates forming the sides of the water section; a top portion greater in height than the side portions of the tank and of less width than the body of the tank, said top section having horizontal portions which form a running board on each side of the central portion, the central portion being flat on top; angle braces at the sides of the tank; and angle braces extending under the flat portion of the top section and under the horizontal portions of the top section, acting to reinforce the top section.

5. The combination in a tender tank having side walls, of a top plate of greater height than the side portions and of less width than the body of the tank, and having depressed portions at each side secured to the side walls of the tank, said depressed portions forming the running boards of the tender; and a dished rear head welded to the top plate,

shaped to fit the top plate and side walls of the tender, and welded to the side walls.

6. The combination in a tender tank, of side plates; and a top plate greater in height than the side plates and less in width than the tender, the top plate having vertical sides and horizontal portions beyond the sides, which form a running board at each side of the central portion, the top, vertical sides and horizontal portions being made of a single plate extending from one side of the tender to the other.
